UNITED STATES PATENT OFFICE.

FREDERICK O. BULLIS, OF ROCHESTER, NEW YORK, ASSIGNOR, BY MESNE ASSIGNMENTS, TO THE ACME COASTER-BRAKE CO., OF SAME PLACE.

DESIGN FOR A GEAR-WHEEL.

SPECIFICATION forming part of Design No. 34,547, dated May 21, 1901.

Application filed May 21, 1900. Serial No. 17,490. Term of patent 14 years.

To all whom it may concern:

Be it known that I, FREDERICK O. BULLIS, of Rochester, in the county of Monroe, in the State of New York, have invented and produced a new and original Design for Gear-Wheels, of which the following is a specification, reference being had to the accompanying drawings, forming part thereof.

Figure 1 is an edge view of a gear-wheel embodying my design. Figs. 2 and 3 are opposite face views of said gear-wheel. Fig. 4 is a vertical sectional view taken on line 4-4, Fig. 2.

The leading feature of my design consists in a gear-wheel having the contiguous side faces of its teeth formed with lengthwise grooves.

A is a gear-wheel embodying my design, *a* the teeth of said gear-wheel, and *a'* the length-

wise grooves formed in the contiguous side faces of the teeth *a*.

A gear-wheel embodying my design presents a pleasing and characteristic appearance.

What I claim is—

The design for a gear-wheel, substantially as herein shown and described.

In testimony whereof I have hereunto signed my name, in the presence of two attesting witnesses, at Rochester, in the county of Monroe, in the State of New York, this 18th day of November, 1899.

FREDERICK O. BULLIS.
